No. 613,263.

Patented Nov. 1, 1898.

A. E. C. GILMOUR.
SOAP HOLDING ATTACHMENT.

(Application filed July 8, 1897.)

(No Model.)

UNITED STATES PATENT OFFICE.

ALFRED E. C. GILMOUR, OF BRIDGEPORT, CONNECTICUT, ASSIGNOR OF ONE-HALF TO HENRY A. LAMB, OF SAME PLACE.

SOAP-HOLDING ATTACHMENT.

SPECIFICATION forming part of Letters Patent No. 613,263, dated November 1, 1898.

Application filed July 8, 1897. Serial No. 643,923. (No model.)

To all whom it may concern:

Be it known that I, ALFRED E. C. GILMOUR, a citizen of the United States, and a resident of Bridgeport, in the county of Fairfield and 5 State of Connecticut, have invented certain new and useful Improvements in Soap-Holding Attachments, of which the following is a specification.

My invention relates to attachments for 10 pipes or faucets, and particularly to soap-holding attachments designed to be connected to pipes or faucets and to furnish a solution of soap directly therefrom and at the same time permit pure water to be drawn from the 15 faucet, if desired; and my present invention is an improvement upon the invention shown and described in the patent granted to me January 28, 1896, and numbered 553,751.

My invention consists in the novel means 20 provided for obtaining soap solution or pure water at will, in the novel means employed for clamping together the soap receptacle or holder and cover for same, and for forming a water-tight joint between said cover and the 25 faucet-holding attachment. Further, to provide a simple means for firmly securing the soap-holding attachment to the faucet. These and other advantages will be more fully set forth in the following specification, and such 30 features believed to be novel particularly pointed out in the claims.

To enable others to understand my invention, reference is had to the accompanying drawings, in which—

35 Figure 1 represents a side elevation of my improved soap-holding attachment, broken view of a faucet-spout, and dotted view of the soap-holding receptacle thrown around to permit clear water to pass through the faucet. 40 Fig. 2 is an upper plan view of the attachment. Fig. 3 is central sectional view of the attachment through line α of Figs. 1 and 2. Figs. 4 and 5 show modified constructions.

Its construction and operation are as follows:

45 1 is an attachment-support adapted to embrace a spout, faucet, pipe, or other liquid-discharging device. 2 is a rubber bushing placed within the said support and adapted to fit 50 directly over the end 3 of the faucet. 4 is a taper head on the lower end of said rubber

bushing, whose purpose will hereinafter be more fully explained.

5 is a clamping-screw carried by support 1, and on the inner end of this screw is the clamp- 55 ing-shoe 6, adapted to partially embrace the rubber bushing and securely hold the said support to the faucet, tube, or other like discharge-outlet.

7 is the soap-holding receptacle, and 8 is 60 the cover therefor. This cover has the central tapered depression 9 to engage with the tapered head 4 of the rubber bushing, whereby not only a tight joint is made between said cover and the faucet, but this head also prevents the accidental withdrawal of the rubber bushing from the support 1. At the bottom of this depression is the perforated dia- 65 phragm 10, through which the water passes in fine jets to the interior of the soap-recep- 70 tacle. 11 is a shallower depression in the upper part of the cover and at the mouth of the larger depression 9 to admit the flanged portion 12 of the support 1.

13 is a locking-lever pivotally supported in 75 the pin 14 of the upper surface of the cover, whose projecting lip 13^a is adapted to engage with the flange 12 of support 1 and securely lock the soap-holding attachment to the said support and at the same time make a tight 80 joint between the before-mentioned rubber bushing and the cover.

The cover 8 has the skirt 8^a overhanging the upper part of the soap-receptacle 7. 15 is a longitudinal slot in such skirt, and 16, Figs. 85 1 and 2, is a pin attached to said receptacle to engage such slot. The depression 17 in the beading 8^b of said skirt serves as means whereby said pin is released from the slot 15 when necessary to swing the soap-holder 90 around. The mechanism necessary to accomplish this consists of the ears 18, projecting from the support 1, which ears carry the pin 19.

20 is a hinged projection rising rigidly from 95 the cover 8 and having the slot 21, adapted to loosely embrace the pin 19. This slotted hinge projection may be made of wire or other suitable material.

The mechanism necessary to open the soap- 100 receptacle, so as to replenish or cleanse the same, consists of the horizontal slot 22, Fig.

3. In the skirt 8^a and 23 is a wire loop whose upper end is bent at right angles to its vertical portion, which angular end is embraced by said slot to form a hinge portion and is secured to the soap-receptacle, while the lower end of this loop is secured to the bottom edge or discharge-mouth of said receptacle.

7^a is a concentric depression formed in the side of the soap-receptacle to admit the large 10 perforated diaphragm 24, through which the solution is discharged from the receptacle.

The construction of the modification shown at Figs. 4 and 5 is as follows: 25 is a clamp-support adapted to embrace the end of a pipe 15 or faucet, which support is split both vertically and horizontally on opposite sides to give it elasticity and having the ears 26 at the side of the slits through which the clamping-screws 27 pass to draw the sides of said 20 support together to secure it to the faucet. 2^a is a rubber packing ring or bushing and is placed within the metal clamp-support to receive the spout of the faucet. The top or cover 8^c is provided with the socket-shaped 25 top 28 to receive the lower end of the support 25, between which top and clamped bushing is placed the packing-washer 28^a, and such top is also provided with the ears 29 29^a to embrace the locking-lever 30 and the projection 30 31 of said support. 32 is a pin passing through the ears 29^a and projection 31, whereby the cover 8^c is pivotally connected with said support. The locking-lever 30 is pivotally supported on the pin 33 of the ears 29, 35 and such lever is adapted when thrown in the vertical position shown to engage with the lip 34 of the support 25, whereby the locking of the soap-receptacle in its normal position is effected.

40 To retain the soap-receptacle in open position, the spring-catch 35 is attached to the cover of the soap-receptacle, so that when the locking-lever 30 is released from its contact with the lip 34 and the receptacle is 45 swung around on its pivotal support 32 in the direction of arrow *a* the hole 36 in the spring-catch 35 will engage with the projecting end 27^a of the clamping-screw 27 and retain the soap-receptacle in such open position. To release said receptacle, the spring-catch is simply pressed to one side, permitting such receptacle to swing back.

In the modified construction just described the soap-receptacle 7^b is detachably secured 55 to the cover by means of the coarse rolled teeth 37.

38 is a passage-way through the clamp-support and socket-shaped top for the admission of water to the interior of the soap-receptacle.

60 It will be observed that (see Fig. 2) the support 1 is elongated, which is done both to make room for the shoe 6 and to accommodate for different sizes of faucet-nozzles.

The operation of the construction shown at 65 Figs. 1, 2, and 3 is as follows: When clear water is needed, the lever 13 is turned sufficient to release its engagement with the flange

12 of the support 1 when all of that portion of the soap-holding attachment below such support is swung around into the dotted position shown at Fig. 1 and when it has reached its extreme outward position the slotted hinge projection will allow said attachment to drop sufficient to permit the upper end of such hinge projection to engage with the side of 75 the support 1, and thereby form a leverage to support the said attachment in its vertical position. Raising the device until the end of the slot 21 reaches the pin 19 it can be swung into its normal position again and 80 locked. As the object sought to be attained in hinging the soap attachment to the support is to provide ready means whereby such attachment can be temporarily removed from below the discharge-mouth of the faucet, so 85 as to draw clear water and also to form a closer joint between the cover 8 and the head 4 of the rubber bushing 2 when the said attachment is swung around into its normal position and clamped, it is quite evident 90 that the said attachment can be removed entirely when carried around into the dotted position shown at Fig. 1, and in order to do this a break or opening could be made in one side of the slotted projection 20 or in any 95 other suitable way, so that the said attachment may be temporarily removed. However, as its removal would endanger its being lost or damaged it is desirable that it should remain connected in the manner substantially as shown. To gain access to the interior of the soap-receptacle 7 to replenish or cleanse the same, it is turned horizontally sufficient to release the pin 16 from its slot 15 and 17 when the said receptacle is swung on 100 its wire support 23 in the direction of arrow 105 *b*, Fig. 3, whereupon the said wire support will pass through the slot 22 of the skirt 8^a and turn outward, operating somewhat similar to the hinge projection for the whole attachment previously described. The wire support or hinge 23 serves also as means for gripping the soap-receptacle when the same is being horizontally turned, thus overcoming that tendency to slip in the hand when the 110 outer surface is polished. This supporting-wire need not extend to the lower end of the receptacle, but may be attached thereto, but higher up.

It will be observed that there is considerable difference in the areas of the two perforated diaphragms 10 and 24, the upper one being much the smaller of the two. This feature is important, as the smaller one regulates the flow of the incoming water to the 120 capacity of the soap-receptacle and its ability to discharge as fast as the water becomes thoroughly impregnated with the soap.

Having thus described my invention, what I claim as new, and desire to secure by Letters 130 Patent, is—

1. An improvement in soap-holding attachments, consisting of a support adapted to be detachably secured to a faucet, tube or other

like device, a soap-holding device hinged to said support and adapted thereby to swing to one side for the purpose described, means for securing it in an open position, for the purpose set forth.

2. An improvement in soap-holding attachments, consisting of a support adapted to be detachably secured to a faucet, tube or other like device, a soap-holding receptacle and its cover, said cover hinged to said support so that said cover and receptacle may swing to one side of the faucet, for the purpose described, means for locking both in an open and closed position, for the purpose set forth.

15 3. An improvement in soap-holding attachments, for pipes, &c., consisting of a support adapted to be detachably secured to a faucet, a soap-receptacle and its cover, a central inclined depression or seat in said cover, a rubber packing-bushing in said support, a head on such bushing having inclined sides adapted to engage the inclined sides of said depression and thereby effect a tight joint between said support and cover, the bottom of said 20 depression perforated, combined with a larger perforated diaphragm within the soap-recep-

tacle, said cover hinged to said support so that the soap-holding device may be swung to one side of the faucet, means for securing said soap-holding device both in an open and closed position, for the purpose set forth.

4. An improvement in soap-holding attachments, for pipes, faucets, &c., consisting of a support adapted to be detachably secured to a faucet or other like device, a soap-holding 35 receptacle and its cover, said cover hinged to said support and adapted to swing to one side of the faucet, perforated partitions or diaphragms between which the soap is placed, means for effecting a tight joint between said 40 cover and support, said soap-holding receptacle connected to its cover so that it can be opened therefrom to replenish or cleanse it, for the purpose set forth.

Signed at Bridgeport, in the county of Fairfield and State of Connecticut, this 26th day of June, A. D. 1897.

ALFRED E. C. GILMOUR.
